UNITED STATES PATENT OFFICE.

FRANK LA BARE, OF OWATONNA, MINNESOTA, ASSIGNOR TO OWATONNA MANUFACTURING CO., OF OWATONNA, MINNESOTA, A CORPORATION.

CHURN.

No. 819,290.

Specification of Letters Patent.

Patented May 1, 1906.

Application filed July 17, 1905. Serial No. 270,051.

To all whom it may concern:

Be it known that I, FRANK LA BARE, of Owatonna, Steele county, Minnesota, have invented certain new and useful Improvements 5 in Churns, of which the following is a specification.

My invention relates to combined churns and butter-workers; and the object of the invention is to provide means for allowing the 10 buttermilk to drain off and escape from the churn during the operation of working the butter.

The invention consists generally in providing means for locking the churn-door in a 15 nearly but not entirely closed position, leaving a narrow crack between the door and its seat for drainage purposes.

Further, the invention consists in various 20 constructions and combinations, all as hereinafter described, and particularly pointed out in the claims.

In the accompanying drawings, forming a part of this specification, Figure 1 is a perspective view of a portion of a churn and 25 cover or door with my invention applied thereto. Fig. 2 is a transverse sectional view. Fig. 3 is a detail sectional view on the line $y-y$ of Fig. 2, showing the door in a partially but not entirely closed position. Fig. 30 4 is a similar view showing the door in its closed position.

In the drawings, 2 represents a churn having the usual opening 3 and a casting 4 extending around the edge of said opening and 35 provided with a seat 5 for a gasket 6. A door 7 is hinged on one side of said opening, preferably by means of the hooks 8, engaging spring-straps 9, secured to the churn. Bolts 10 have threaded ends passing through the 40 straps 9 and provided with nuts, by means of which the straps and the hooks can be drawn down toward the churn to increase the pressure of the door on the gasket. Cam-levers 11 are mounted on the churn on the side opposite the hinges and at each end and are adapted to bear upon the cover and lock it firmly in its closed position during the churning operation. It is desirable during the 45 working of the butter to leave the door open a little for drainage purposes, and at the same time it is necessary to secure the door to prevent any possibility of its escaping from its fastenings and opening wider than was intended. I therefore provide plates 12,

slidably secured on the edge of the door opposite its hinged side by means of pins 13, passing through slots 14 in said plates and into the edge of the door. Handles 15 are provided on said plates to permit their convenient lengthwise movement. Each plate is 55 provided in its lower edge with a recess 16, which is adapted to coincide with a lug 17 when it is desired to entirely close the door. Whenever the operator wishes to lock the door in a partially-closed position, the plates 60 are moved, as shown in Fig. 3, so that when the door is closed the lugs 17 will not coincide with their recesses, but engage the plates at one side thereof and prevent the door from being entirely closed. The cam-levers are 65 then swung round to their closed position, pressing the door down firmly upon the lugs 16 and leaving a crack between the door and its seat of sufficient width to drain the churn during the butter-working operation. When- 70 ever desired, the cam-levers may be loosened, the plates moved to a position to allow the lugs to enter the recesses therein, and then the door may be entirely closed. The depth of the slots 16 and the height of the lugs 17 75 will regulate the width of the crack between the door and its seat, it being only necessary to provide sufficient space or clearance to secure the desired drainage. I have shown separate plates provided at each end of the 80 churn-door; but they may be connected or formed in one piece, if preferred. The han- 85 dles for operating the plates may also be used in opening and closing the churn-door.

I claim as my invention—

1. The combination, with a churn and butter-worker provided with an opening and a door therefor, of means arranged to temporarily prevent the complete closing of said door leaving a narrow crack between it and 95 its seat, and means for locking said door in its nearly but not entirely closed position.

2. The combination, with a churn and butter-worker having an opening and door therefor, of sliding means mounted on said door, means mounted on the churn in the path of said sliding means to engage the same and prevent the complete closing of said door, and means for locking the door in its nearly but not entirely closed position.

3. The combination, with a churn and butter-worker having an opening and a door therefor, of a plate having a recess mounted

on said door, a lug provided on the churn to enter said recess, said plate being movable to prevent said lug from entering said recess, and means for locking said lug in engagement with said plate and said door in its partially-closed position, substantially as described.

4. The combination, with a churn and butter-worker having an opening and door therefor, of plates slidably mounted on said door and having recesses in their edges, lugs provided on the churn and adapted to enter said recesses and allow the complete closing of said door or engage said plates at one side of said recesses and prevent the complete closing of said door, and cam-levers arranged to engage said door and lock it in its nearly but not entirely closed position.

5. The combination, with a churn and butter-worker having a door-opening and door therefor hinged at one side of said opening, of plates 12 slidably mounted on the edge of said door opposite from said hinges and provided with recesses in their lower edges, lugs 17 provided near the edge of said opening and adapted to enter said recesses and allow the complete closing of said door and engage

the lower edge of said plates when they are moved lengthwise on said door and prevent the complete closing of the same, and cam-levers arranged to engage the top of said door and lock it in its closed or partially-open positions, substantially as described.

6. The combination, with a revolving receptacle provided with a peripheral opening 35 and a door therefor, of means arranged to temporarily prevent the complete closing of said door leaving a narrow crack between it and its seat, and means for rigidly securing said door in its closed position or in its nearly 40 but not entirely closed position.

7. The combination with a churn and butter-worker provided with a door and opening therefor, of means for temporarily locking said door in a partially-open position leaving 45 a narrow crack between it and its seat and preventing it from moving in either direction, substantially as described.

In witness whereof I have hereunto set my hand this 10th day of July, 1905..

FRANK LA BARE.
